UNITED STATES PATENT OFFICE.

BYRON GUNNER, OF HILLBURN, NEW YORK.

PUZZLE.

1,121,495.

Specification of Letters Patent.

Patented Dec. 15, 1914.

Application filed May 13, 1913. Serial No. 767,277.

To all whom it may concern:

Be it known that I, BYRON GUNNER, a citizen of the United States, and a resident of Hillburn, in the county of Rockland and State of New York, have invented a new and Improved Puzzle, of which the following is a full, clear, and exact description.

This invention relates to the general class of games and toys and has to do more particularly with a pocket puzzle which calls for a display of a high degree of ingenuity and resourcefulness in effecting its solution, while at the same time the puzzle affords considerable amusement and entertainment.

The general object of the invention is to provide a puzzle of comparatively simple and inexpensive construction and made of such material that it can be conveniently carried in the pocket and which will last a long time, as it is made of durable material.

The invention comprises a body piece made of leather or other suitable flexible material having a novel arrangement of slits and openings in which is threaded a string, ribbon or other flexible key element which is capable of being removed from the body piece by following a predetermined series of movements, steps or manipulations which are very difficult to discover, so that the solution of the puzzle calls for a display of ingenuity, resourcefulness and attention.

For a more detailed understanding of the invention reference is to be had to the accompanying drawing taken in connection with the following description and the claims appended hereto.

In the drawings which illustrate certain embodiments of the invention Figure 1 is a perspective view of the body piece with the ribbon or string element removed. Fig. 2 is a perspective view of the complete puzzle with the string or ribbon element applied thereto; Fig. 3 is a front view showing the preliminary steps in the solution of the puzzle; Figs. 4, 5 and 6 are longitudinal sectional views showing successive steps necessary to the completion of the puzzle and following the steps leading up to Fig. 3; Fig. 7 is a diagrammatic view of the simplest form of the puzzle; and Figs. 8 and 9 are diagrammatic views of slightly more complicated forms of the puzzle.

Referring to the drawings, A designates the body piece of the puzzle which is a strip of leather or other suitable flexible mate-

rial having longitudinal slits 1 and 1^a of suitable length to form between the slits a keeper or loop member 2, there being eyelets 3 and 3^a, if desired, at the ends of the slits 1 and 1^a. The slits do not extend to the ends of the body piece A and intermediate one end of the body piece and the slits is an opening 4 formed by apertures 5 and connecting slits 6, the apertures and slits being so formed that the opening 4 is V-shaped, with the tongue 8 forming one side of the opening. It is to be understood, however, that the opening 4 may be of any other desired form. At the opposite end of the body piece A are openings 8 and 9 which may be formed in the same way as the opening 4. The removable string or other flexible element B is shown as a length of baby ribbon having stops 10 applied to the ends thereof, these stops being in the form of rings or any other suitable devices so that the removable element B cannot be taken out of the body piece except by following the various prescribed movements hereinafter to be described. When the removable element B is applied to the body piece A the portion b' crosses the keeper or loop member 2 at the upper end thereof, thence passes through the upper openings 3 and 3^a upwardly therefrom at the back of the body piece A and through the opening 4. The two members b² and b³ of the flexible element B extend downwardly at the front of the body or piece A, passing under the crossing portion b' and successively through the openings 8 and 9, as clearly shown in Fig. 2. This is the condition of the puzzle when the solution begins.

The first step is to draw the middle part b' of the ribbon element downwardly and pass it successively through the openings 8 and 9, as shown in Fig. 3, it being necessary to double or bend the flexible body piece A in this operation. The rings or stops 10 are then passed through the loop formed by the portion drawn downwardly through the openings 8 and 9. When this is done the body piece is pulled out flat and in doing so the ribbon element D will assume the position shown in diagram Fig. 9. The description of the solution of the problem from now on will apply to forms shown both in Figs. 2 and 9. The next step consists in doubling the body piece A on the line a, b, Fig. 2, so as to bring the openings 110

8 and 9 opposite each other, the folding of the body piece being backward and the relation of the parts in the position they now occupy, as shown in Fig. 4. The body piece A is then folded forwardly on the line c, d, Fig. 2, so as to bring the opening 4 in line with the openings 8 and 9, as shown in Fig. 5. The keeper or loop member 2 is then threaded forwardly through the openings 4, 8 and 9, as shown in Fig. 6. During these folding operations no attention is paid to the ribbon element B, but when the loop member 2 is threaded through the openings 4, 8 and 9 the two ends of the ribbon element B are grasped and the ribbon pulled forwardly, and in so doing it will finally assume the position shown in Fig. 6, when the ribbon can then be pulled out of the looped or double keeper 2. The body piece with the ribbon or flexible element B removed is then straightened out, which means that the puzzle is solved, as the elements A and B are separated. In replacing the ribbon element B the body piece A is folded and manipulated to bring about the position shown in Fig. 6 when the ribbon element B is inserted in the looped member 2. The two ends of the body piece A are then grasped, one in each hand, and pulled apart so as to straighten the body piece, whereupon the element B will be in the position shown in Fig. 9. It now remains to pull down the middle portion b' of the ribbon element B and pass such middle portion b' through the openings 8 and 9, as shown in Fig. 3, when the stops 10 are placed through the loop formed by the middle portion b'. When this is done the body piece A is pulled out straight so that the ribbon element B will assume the position shown in Fig. 2.

In solving the simplest form of the puzzle shown in Fig. 2, the body piece A' is first forwardly doubled approximately on the line e, f, and then the keeper member 2^a is passed through the opening 4^a in the same manner shown in Fig. 6, and the ribbon element B' can be removed. In solving the puzzle shown in Fig. 8 the body piece A² is doubled forwardly approximately on the line g, h, so as to bring the opening 8^a opposite the opening 4^b, and then the keeper member 2^b is passed through the openings 8^a in order to enable the ribbon element B² to be removed. Of course, in reapplying the

ribbon element the steps just described are reversed.

In the following claims the term "ribbon element" is intended to include a chain, cord, string or any other flexible device which will serve the desired purpose.

From the foregoing description taken in connection with the accompanying drawings, the advantages of the method of operation and of the device shown will be readily understood by those skilled in the art to which the invention appertains, and while I have described the device which I now consider to be the best embodiment thereof, I desire to have it understood that the device shown is merely illustrative, and that such changes may be made when desired as are within the scope of the appended claims.

Having thus described my invention, I claim as new and desire to secure by Letters Patent:

1. A puzzle of the class described comprising a flexible body piece having openings adjacent its ends, and a flexible keeper member between the openings; and a removable ribbon element crossing the keeper member and passing through the opening at one end and thence through the opening at the opposite end, said ribbon element having stops larger than the said openings to prevent their passage through the latter.

2. A puzzle of the class described comprising a body piece having a pair of openings at one end and bendable between the openings and an opening at the opposite end, said body piece being bendable at a point intermediate its ends, there being longitudinal slits in the intermediate portion of the body piece to form a keeper member adapted when doubled to be inserted through said alining openings; and a removable ribbon element normally crossing the keeper member and passing through the single opening at one end and successively through the two openings at the other end of the body piece, there being stops on the ends of the ribbon element.

In testimony whereof I have signed my name to this specification in the presence of two subscribing witnesses.

BYRON GUNNER.
